UNITED STATES PATENT OFFICE.

MAX GOODMAN, OF NEW YORK, N. Y.

DESIGN FOR A DOLL OR SIMILAR ARTICLE.

Application filed September 28, 1925. Serial No. 14,930. Term of patent 14 years.

To all whom it may concern:

Be it known that MAX GOODMAN, a citizen of the United States, and resident of the city of New York, in the county of Kings and State of New York, has invented a new, original, and ornamental Design for Doll or Similar Article, of which the following is a specification, reference being had to the accompanying drawing, forming part thereof, in which the figure is a perspective view of a doll embodying my new design.

I claim:

The ornamental design for a doll or similar article as shown.

Dated New York city, August 31, 1925.

MAX GOODMAN.
